TIME SIGNALING SYSTEM

John I. Bellamy, Brookfield, and Rodney G. Richardson, Chicago, Ill., assignors, by mesne assignments, to Associated Electric Laboratories, Inc., Chicago, Ill., a corporation of Delaware

Application August 28, 1930, Serial No. 478,324

35 Claims. (Cl. 179—2)

The present invention relates in general to time signaling systems, being concerned more particularly with a time signaling device for telephone systems.

5 The object of the invention, broadly stated, is the provision of new and improved circuits and apparatus for transmitting the time of day to subscribers in a telephone system.

A further object is the provision of a trunk 10 circuit adapted to connect automatic telephone subscribers to the time signaling device. This enables any subscriber, by merely operating his calling dial to transmit the proper number, to establish a connection with the time signaling 15 device and thus ascertain the time of day. The number of simultaneous connections to the time signaling device is governed by the number of time trunk circuits provided.

One of the features of the invention is the arrangement for providing a tick-tone signal to 20 indicate to the subscriber that a connection is established to the time signaling device.

Another feature is the arrangement for connecting the subscriber to the time signaling conductors after a time trunk relay group is seized. 25 By this arrangement, the subscriber is disconnected from the tick-tone signaling conductors and connected to the time signaling conductors when the time signaling device is in position to transmit a complete time signal. This prevents 30 any subscriber from being connected to the time signaling conductors when the time signaling device is in the process of transmitting a time signal.

35 A further feature is the arrangement for disconnecting the subscriber from the time signaling conductors and connecting him to the busy signaling conductors after he has received the same complete time signal twice. However, if the time is changed while he is listening to the first time signal, he will receive the complete time signal of the old time and two complete additional signals of the new time before he is disconnected from the signaling conductors and connected to the busy signaling conductors.

40 A still further feature is the arrangement for providing a special tone signal to indicate to the subscriber that the time has changed and that the next signal will be of the new time.

45 The foregoing objects and features together with others not specifically mentioned at this time will be further discussed in connection with the detailed description of the operation of the various circuits.

50 55 The accompanying drawings comprising Figs.

1 to 3, inclusive, show by means of the usual circuit diagrams a sufficient amount of equipment in a system embodying the invention to permit the invention to be readily described and understood.

5 Referring now to the drawings, in Fig. 1 is shown a time trunk circuit TTC which is accessible to subscribers in an automatic telephone system. Conductors 5, 6, and 7 are connected to bank contacts, such as contacts 2, 3, and 4, 10 of a selector in the exchange. The selectors used can be any of the standard type selectors used in regular practice, such as the selector shown in Fig. 63 and described on pages 62 to 65, inclusive, of Smith and Campbell's "Automatic Telephony", second edition, published in 1921 by McGraw-Hill Book Company, Inc., New York.

Conductors 26 to 34, inclusive, are common to a plurality of time trunk circuits TTC. The equipment shown to the right of the conductors 20 26 to 34, inclusive, together with the equipment shown in Fig. 2, constitute the time signaling device.

The contacts 35 are momentarily closed once 25 every minute by a master clock and are arranged to control the operation of the registers HR, TR, and UR shown in Fig. 2, as will be described hereinafter.

The buzzers B1 to B4, inclusive, shown above 30 and to the right of the master clock, are each 35 tuned to a different predetermined audible pitch or frequency. The buzzer designated B1 is arranged to transmit intermittent pulses to the subscriber of a low, mellow tone indicative of the hour. The buzzer designated B2 transmits 40 intermittent pulses of a slightly higher pitch or frequency indicative of the tens of minutes, and the buzzer designated B3 transmits intermittent pulses slightly higher in pitch or frequency than buzzer B2, indicative of the units of minutes. By 45 this arrangement the subscriber receives three distinct intermittent tone signals indicative of the hour, tens and units of minutes, respectively. The buzzer designated B4 transmits a special short pulse tone signal of a very high audible 50 pitch or frequency every minute to indicate to the subscriber that the time has changed and that the next time signal to be transmitted by buzzers B1—B3 will be a new signal corresponding to the changed time.

The relays designated 110 and 111 are continuously operating and act as an interrupter for the counting relays 210—223 shown in Fig. 2, and for buzzers B1—B3 shown in Fig. 1.

The relays designated 105 and 106 are two step sequence relays. They are arranged to prepare operating circuits over the various registers, HR, TR, and UR, shown in Fig. 2, in proper sequence, and are also arranged to prepare the circuits for the various buzzers B1 to B3, inclusive, in sequence with the circuits of the various registers.

Relay 107 is a two-step relay with a weighted spring combination, similar to that disclosed in Patent No. 1,641,256, granted to John Erickson September 6, 1927, in addition to the regular spring combination. Relay 107 energizes in its second step, after a complete time signal has been transmitted, and causes the weighted spring to vibrate. The vibrating contact does not close a circuit until it comes to rest and in this way provides an additional delay between the transmission of each complete time signal.

Fig. 2 shows three registers, the hours register HR, the tens of minutes register TR, and the units of minutes register UR. The hours register HR is a 25-point rotary switch, similar to that disclosed in Patent No. 1,693,027, granted to John Erickson November 27, 1928. The tens and units of minutes registers TR and UR, respectively, are standard rotary mechanisms of the 11-point type and are similar in construction to the above-mentioned 25-point rotary switch. The rotary switches are of the step-by-step type in which the wipers move in a forward direction only, and in which the wipers are advanced when the stepping magnet retracts its armature rather than when the stepping magnet attracts its armature. The units of minutes register UR advances its wipers one step each minute, the tens of minutes register TR advances its wipers one step for every ten steps of the wipers of the units of minutes register UR, and the hours register HR advances its wipers one step for every six steps of the wipers of the tens of minutes register TR. In this way the exact time of day is always registered by the time signaling device.

Relays 212 to 223 are counting relays wherein the first relay of a pair is energized by a pulse from the contacts of the interrupter relay 110 and the second relay of the pair is energized and locked up in series with the first when the potential for operating the first relay is removed. When all the counting relays are locked up the circuit is transferred at relay 223 and the counting relays are deenergized in the same order in which they were energized. Each of the pairs of counting relays close testing circuits for the stop relay 112 when one or the other of the pair is energized and the other deenergized. If a circuit is closed to the stop relay all the energized counting relays are deenergized.

Relays 210 and 211 are a pair of pick-up relays, similar to the regular counting relays. Relay 210 controls the operating circuit for the buzzers B1 to B3, inclusive, and relay 211 controls the pick-up circuit for connecting the time trunk circuit TTC to the time signaling device.

Fig. 3 illustrates a simplified time trunk circuit that provides a holding bridge for the selector having access to the time signaling device. This time trunk circuit, when used in place of the time trunk circuit TTC, permits the subscriber to listen to the time signals as long as he desires. With this circuit the subscriber is immediately connected to the time signaling conductors as soon as it is seized by the selector and it does not release until the subscriber hangs up.

In the drawings the slow-acting relays are denoted by shading the lower portion of their cores, or by making the upper portion of their cores solid black, depending upon whether the relay is merely slow to release or is also slow to operate. A shaded portion on the lower end of the core indicates that the relay is slow to release after its energizing circuit is opened, but is not appreciably slow to operate when an energizing circuit is closed. A solid black portion on the upper end of the core indicates that the relay is slightly slow to operate when an energizing circuit is closed in addition to being slow to release after its energizing circuit is opened.

The invention having been described in general, a detailed description of the operation of the apparatus shown will follow.

Automatic telephone subscriber calling the time signaling device

It can be assumed that the time signaling device is in the position shown on the drawings and that an automatic telephone subscriber desires to ascertain the time of day.

When the subscriber removes his receiver he is automatically connected, in the usual manner, to a selector. By dialing the number assigned to the time signaling device, the wipers of the selector are stepped up to the desired level and are automatically rotated across the bank associating its wipers with bank contacts 2, 3, and 4 of the selector, assuming that the trunk connected to these contacts is idle.

When the selector associates its wipers with contacts 2, 3, and 4, shown to the left of the time trunk circuit TTC in Fig. 1, a circuit is immediately closed from ground, lower winding of line relay 10, positive line conductor 7, bank contact 4 and positive line wiper of the selector, subscriber's loop, negative line wiper and bank contact 2 of the selector, negative line conductor 5, upper winding of line relay 10, to battery. Line relay 10, upon energizing, at armature 41 connects ground to the release trunk conductor 6, for holding the selector and preceding switches 45 operated. Line relay 10, upon operating, also closes a circuit for pick-up relay 11 from battery, winding of relay 11, armature 39 and its front contact, armature 18 and its resting contact, resting contact controlled by armature 45, pick-up conductor 32, armatures 115 and 116 and their respective resting contacts, conductor 131, armature 224, to ground. Upon energizing, pick-up relay 11 closes a locking circuit for itself from ground at armature 45 and its front contact and at the resting contact controlled by armature 45 disconnects its original energizing circuit over the pick-up conductor 32. At armatures 43 and 46 and their front contacts, pick-up relay 11 connects the subscriber's line, over conductors 5 and 7 and condensers 12 and 13, to the time signaling conductors 28 and 29 and at armature 44 and its front contact prepares a circuit for subsequently disconnecting the subscriber from the time signaling conductors, as will be hereinafter described.

The time trunk circuit is now in position to permit the time signals transmitted over conductors 28 and 29 to be received by the subscriber.

Transmission of time signal

It has been mentioned before that the equipment is in the position shown on the drawings when it is seized by the subscriber. The posi-

tion of the registers, shown in Fig. 2, should be particularly noted. The hours register HR has its wipers 201—202 resting on the first set of contacts of the banks, the tens of minutes register TR has its wipers 204—205 resting on the third set of contacts of its banks, and the units of minutes register UR has its wipers 207—208 resting on the eighth set of contacts of its banks. It can be seen, by the position of the wipers, that 10 the time to be transmitted by the time signaling device is 1:38 o'clock.

The interrupter relays 110 and 111, shown in Fig. 1, are self interrupting and are continuously operating as will now be described.

15 Relays 110 and 111 are shown connected in series, but relay 111 is short circuited from ground at armature 117 and its resting contact. Relay 110 energizes from ground at armature 117 and its resting contact and removes the short-circuit 20 from relay 111, energizing it in series with relay 110. Relay 111, upon energizing, short circuits relay 110 at armature 120 and its front contact and relay 110 deenergizes. Upon deenergizing relay 110 short circuits relay 111 at armature 25 117 and its resting contact. Relay 111 deenergizes and removes the short circuit from relay 110 at armature 120 and its front contact, permitting relay 110 to pull up again. It should be noted that the operation of the two relays is 30 comparatively slow because both relays are slow to energize and also slow to release after the energizing circuit is opened.

The first time interrupter relay 110 operates a circuit is closed at armature 118 and its front 35 contact for pickup relay 210, shown in Fig. 2, from ground, armature 225 and its resting contact, conductor 130, armature 118 and its front contact, armature 133 and its resting contact, conductor 129, armatures 226—232 and their 40 respective resting contacts, winding of pick-up relay 210, to battery. Upon energizing, pick-up relay 210 prepares a circuit at armature 233 and its front contact for relay 211, and at armature 240 and its front contact it prepares a circuit 45 for the tuned buzzer B1.

Interrupter relay 110, upon deenergizing as has been hereinbefore described, closes a circuit at armature 119 and its resting contact for buzzer B1 from ground, armature 240 and its front contact, 50 conductor 132, armatures 119, 134, and 135 and their respective resting contacts, interrupter contacts and winding of buzzer B1, to battery. Buzzer B1 vibrates and an alternating current of a particular frequency flows through its associated 55 condenser, conductor 36, primary winding of transformer 23, to ground. An alternating current of the same frequency flows in the secondary winding of transformer 23 and over the time signaling conductors 28 and 29, armatures 43 and 60 46 and their front contacts, condensers 12 and 13 and conductors 5 and 6, to the subscriber's telephone.

Upon deenergizing, interrupter relay 110 also 65 opens the energizing circuit for pick-up relay 210, at armature 118 and its front contact. However, pick-up relay 210 locks up in series with relay 211, as soon as its original energizing circuit is 70 opened from battery, winding of pick-up relay 210, armature 233 and its front contact, winding of relay 211, conductor 128, armature 136 and its resting contact, to ground. Relay 211 energizes and at armature 224 and its resting contact 75 opens the pick-up circuit, preventing any other time trunk circuits similar to time trunk circuit TTC from connecting a subscriber to the time

signaling conductors 28 and 29 at this time. The pick-up circuit is opened at approximately the same time the tone signal is being transmitted over conductors 28 and 29 and prevents any subscriber from being connected to the time signaling conductors while a time signal is in the process of being transmitted. At armature 232 and its front contact, relay 211 prepares a circuit for counting relay 212.

Interrupter relay 110, upon energizing a second 10 time, opens the circuit at armature 118 and its resting contact for buzzer B1 and it stops vibrating. Relay 110 also closes a circuit again at armature 118 and its front contact, from ground, armature 225 and its resting contact, conductor 15 130, armature 118 and its front contact, armature 133 and its resting contact, conductor 129, armatures 226—232 and their respective resting contacts, armature 232 and its front contact, winding of counting relay 212, to battery. Upon energizing, counting relay 212 prepares a locking circuit 20 for itself, at armature 234 and its front contact in series with counting relay 213 and at armature 241 and its front contact closes a circuit from ground, armatures 139 and 140 and their resting 25 contacts, conductor 124, wiper 202 and the first bank contact of the hours register HR, armature 241 and its front contact, armature 253 and its resting contact, conductor 127, winding of the slow-acting stop relay 112 to battery. Stop relay 30 112 subsequently energizes and at armature 138 and its front contact closes a locking circuit for 35 itself from ground, armatures 137 and 138 and their respective front contacts, winding of stop relay 112, to battery. At armature 136 and its 40 back contact, stop relay 112 removes the holding ground from conductor 128, releasing relays 113, 210 and 211, and at armature 133 and its resting contact opens the energizing circuit for counting relay 212. At armature 116 and its resting contact, stop relay 112 also opens the pick-up circuit 45 over conductor 32. Relay 210, upon deenergizing, opens the circuit for the buzzers over conductor 132, at armature 240 and its front contact. Relay 211, upon restoring to normal, closes a point in 50 the pick-up circuit over conductor 32 at armature 224 and its resting contact. The pick-up circuit is now held open at armature 116 and its resting contact. Relay 212, upon deenergizing, opens the original energizing circuit for stop 55 relay 112 at armature 241 and its front contact. Upon deenergizing, relay 113 opens the locking circuit for stop relay 112 at armature 137 and its front contact, and at armature 141 and its front contact it removes the short circuit from the 60 lower winding of sequence relay 105. Sequence relay 105 now locks itself in its second step from ground, resting contacts controlled by armature 144, contact A of sequence relay 105, both windings of relay 105 in series, to battery. At armature 140 and its front contact, sequence relay 105 transfers the marking ground circuit over conductor 124 and wiper 202 of the hour register HR to conductor 123 and wiper 205 of the tens of 65 minutes register TR. At armature 135 and its front contact, sequence relay 105 transfers the circuit from the hours buzzer B1 to the tens of minutes buzzer B2 and at armature 115 and its resting contact it opens another point in the pick-up circuit over conductor 32. Also relay 105 prepares a circuit for the upper winding of sequence relay 106 at armature 143 and its front contact.

Relays 112 and 113 are slow to energize and slow to release in order to provide a slight delay between the transmission of the hour and tens of 70 75

minutes signals and also between the tens and units of minutes signals.

It was mentioned above that the locking circuit for stop relay 112 was opened. Stop relay 112 subsequently deenergizes and at armature 118 and its resting contact closes a point in the pick-up circuit over conductor 32, which is now opened at armature 115 only. At armature 136 and its resting contact, relay 112 closes an energizing circuit for relay 113. Relay 113, upon energizing, prepares a locking circuit for relay 112, at armature 131 and its resting contact and at armature 141 and its front contact it closes a circuit from ground, armature 141 and its front contact, armature 142 and its resting contact, armature 143 and its front contact, upper winding of sequence relay 106, to battery. Sequence relay 106 energizes in its first step, closing contacts A only, and it prepares a locking circuit for itself from ground at the resting contacts controlled by armature 144. It is obvious that the lower winding of the two-step sequence relay 106 is short-circuited by its initial energizing circuit and it cannot operate to its second step until the short circuit is removed. At armature 133 and its resting contact, stop relay 112 again closes the circuit controlled by interrupter relay 110 at armature 118 and its front contact.

The subscriber has now received the first tone signal over conductors 28 and 29 from buzzer B4, which is the hours signal, as has been hereinbefore described.

After stop relay 112 deenergizes, the next time relay 110 energizes a circuit is immediately closed again to pick-up relay 210, at armature 118 and its front contact over the previously traced circuit. Relay 210 operates as before, preparing a locking circuit for itself in series with relay 211, and at armature 240 prepares a circuit for tens of minutes buzzer B2.

Interrupter relay 110 subsequently deenergizes and at armature 119 and its resting contact closes a circuit from ground, armature 240 and its front contact, conductor 132, armatures 119 and 134 and their respective resting contacts, armature 135 and front contact, interrupter contacts of buzzer B2, winding of the tens of minutes buzzer B2, to battery. Buzzer B2 transmits alternating current of a particular frequency over the primary and secondary windings of the transformer 23, conductors 28 and 29, signaling the subscriber in the same manner as has been described in connection with the hours buzzer B1.

Upon deenergizing, interrupter relay 110 also opens the energizing circuit for pick-up relay 210 at armature 118 and its front contact. Pick-up relay 210 locks up in series with relay 211, as soon as its original energizing circuit is opened, over the circuit previously traced for the above relays. Upon energizing, relay 211 opens a point in the pick-up circuit at armature 224 and its resting contact without effect at this time, and prepares a circuit for relay 212 at armature 232 and its front contact. The pick-up circuit, over conductor 32, is now held open, at armature 115 and its resting contact, until the complete time signal is transmitted.

Interrupter relay 110 subsequently energizes again and at armature 119 and its resting contact terminates the first tens of minutes signal to the subscriber. At armature 118 and its front contact it closes a circuit for counting relay 212 as before. Upon energizing, counting relay 212 prepares a locking circuit for itself at armature

234 and its front contact, in series with counting relay 213, and at armature 241 and its front contact it closes a test circuit from stop relay 112 to the first bank contact of the registers. The absence of ground on the first bank contact of the register prevents the stop relay 112 from energizing at this time.

Interrupter relay 110, upon deenergizing again, closes the circuit for the tens of minutes buzzer B2 a second time, at armature 119 and its resting contact starting the transmission of the second signal from buzzer B2 to the subscriber. At armature 118 and its front contact, interrupter relay 110 opens the original energizing circuit for counting relay 212 and at the same time it removes the short circuit from the winding of counting relay 213. Counting relays 212 and 213 lock up in series from battery, winding of relay 212, armature 234 and its front contact, winding of relay 213, conductor 128, armature 136 and its resting contact, to ground. Counting relay 213, upon energizing, opens the test circuit for the first bank contact of the registers at armature 253 and its resting contact, and at armature 231 and its front contact it prepares a circuit for counting relay 214.

Interrupter relay 110 subsequently energizes again, and at armature 118 and its resting contact it opens the circuit for buzzer B2, terminating the second signal from buzzer B2 to the subscriber. At armature 118 and its resting contact interrupter relay 110 closes a circuit for counting relay 214 from ground, armature 224 and its resting contact, conductor 130, armature 118 and its front contact, armatures 226 to 230, inclusive, and their respective resting contact, armature 231 and its front contact, winding of counting relay 214, to battery. Counting relay 214, upon energizing, closes a testing circuit at armature 242 and its front contact from stop relay 112 to the second bank contact of the registers. The absence of ground on the second bank contact prevents stop relay 112 from energizing at this time. At armature 235 and its front contact counting relay 214 prepares a locking circuit for itself in series with counting relay 215. Counting relay 215 is short-circuited for the time being by the initial energizing circuit for counting relay 214.

Interrupter relay 110, upon deenergizing again, closes the circuit for the tens of minutes buzzer B2 a third time, at armature 119 and its resting contact starting the transmission of the third signal from buzzer B2 to the subscriber. At armature 118 and its front contact interrupter relay 110 removes the short circuit from around the winding of counting relay 215 and it opens the original energizing circuit for counting relay 214. Counting relay 214 and relay 215 lock up in series, from ground, winding of relay 214, armature 235 and its front contact, winding of relay 215, conductor 128, armature 136 and its resting contact to ground. Relays 210-215 are all locked to ground at armature 136 of stop relay 112. Relay 215, upon energizing, opens the testing circuit for stop relay 112 at armature 254 and its resting contact and at armature 230 and its front contact it prepares a circuit for counting relay 216.

Interrupter relay 110 energizes as before and at armature 119 and its resting contact opens the circuit of the tens of minutes buzzer B2, terminating the third signal to the subscriber.

At armature 118 and its front contact interrupter relay 110 again closes a circuit to the

counting relays over conductor 128, this time energizing counting relay 216. At armature 243 and its front contact relay 216 closes a testing circuit from the slow-acting stop relay 112 to the third bank contact of the registers. This time a circuit is completed to stop relay 112 from ground, armature 139 and its resting contact, armature 140 and its front contact, conductor 123, wiper 205 and the third bank contact of the tens of minutes register TR, armature 243 and its front contact, armature 255 and its resting contact, conductor 127, winding of stop relay 112, to battery. Stop relay 112 energizes and at armature 138 and its front contact it closes an obvious locking circuit for itself. At armature 136 and its resting contact stop relay 112 removes the locking ground for relays 210 to 215, inclusive, and at armature 133 it opens the circuit for counting relay 216. Relays 210 to 216, inclusive, restore to normal. Pick-up relay 210, upon deenergizing, opens the circuit for buzzer B2 at armature 240 and its front contact, and relay 211, upon deenergizing, closes a point in the pick-up circuit. The pick-up circuit is now held open at armatures 115 and 116 and their respective resting contacts. Counting relay 216, upon deenergizing, opens the original energizing circuit for stop relay 112 at armature 243 and its front contact. The removal of ground from conductor 128, at armature 136 and its resting contact, opens the circuit for the normally energized relay 113 and it deenergizes. At armature 141 and its front contact, relay 113 removes the short circuit from the lower winding sequence relay 106. Sequence relay 106 now locks itself in its second step, from ground, resting contacts controlled by armature 144, contact A of relay 106, both windings of relay 106 in series, to battery. At armature 139 and its front contact, sequence relay 106 transfers the marking ground from conductor 123, connected to wiper 205 of the tens of minutes register TR, to conductor 122, connected to wiper 208 of the units of minutes register UR. At armature 134 and its front contact the signaling circuit is transferred from the tens of minutes buzzer B2 to the units of minutes buzzer B3. Relay 106 prepares a circuit at armature 143 and its front contact for the upper winding of sequence relay 107.

50 Relay 113, upon deenergizing, also opens the locking circuit for stop relay 112. Relays 112 and 113 are slow to operate and slow to release, providing the necessary delay between the transmission of each group of signals. Relay 112 subsequently deenergizes again and closes the pick-up circuit at armature 116 without effect at this time. At armature 136 and its resting contact relay 112 restores the holding ground to conductor 136, causing relay 113 to energize again. At armature 137 and its front contact, relay 113 prepares the locking circuit for stop relay 112, and at armature 141 and its front contact it closes a circuit from ground, armatures 141 and 142 and their respective front contacts, upper winding of sequence relay 107, to battery. Sequence relay 107 energizes in its first step, closing contact A only, and it prepares a locking circuit for itself from ground at the resting contact controlled by armature 144. The lower winding of the sequence relay 107 is short circuited by the initial energizing circuit for the upper winding, preventing it from operating in its second step. At armature 133 and its resting contact, stop relay 112 again closes the interrupter circuit controlled by armature 118 and its front contact,

The subscriber has now heard one signal from the hours buzzer B1 and three distinct signals from the tens of minutes buzzer B2.

Stop relay 112 having deenergized, when interrupter relay 110 subsequently energizes it again closes a circuit for pick-up relay 210. Pick-up relay 210 prepares a circuit at armature 240 and its front contact for the units of minutes buzzer B3, and at armature 233 and its front contact it prepares a locking circuit for itself in series with relay 211. Interrupter relay 110 subsequently deenergizes, completing the first circuit for buzzer B3 from ground, armature 240 and its front contact, conductor 132, armature 119 and its resting contact, armature 134 and its front contact, interrupter springs and winding of the units of minutes buzzer B3, to battery. Buzzer B3 transmits alternating current of a particular frequency over the previously-traced circuit to the subscriber in the same manner as has been described in connection with the hours buzzer B1 and the tens of minutes buzzer B2. Upon deenergizing, interrupter relay 110 removes the short circuit from relay 211, at armature 118 and its front contact, and relays 210 and 211 lock up in series to grounded conductor 128.

It is obvious now that each time the interrupter deenergizes and energizes, with stop relay 112 deenergized and pick-up relay 210 energized, a signal will be transmitted to the subscriber. In addition, each time interrupter relay 110 energizes a circuit is completed to the first counting relay of the next succeeding pair, and upon deenergizing both relays of the pair lock up in series to grounded conductor 128.

It is assumed now that the interrupter relay 110 has energized seven times and has deenergized six times, including the energization required to operate pick-up relay 210. Relays 210 to 221 will be locked to grounded conductor 128 and counting relay 222 will be energized from ground at armature 225 and its resting contact over a circuit including armature 118 and its front contact. During this time the subscriber will have received six distinct signals from the units of minutes buzzer B3. Counting relay 222, upon energizing, closes a testing circuit at armature 246 and its front contact from stop relay 112 to the sixth bank contact of the register. The absence of ground on this contact prevents stop relay 112 from operating at this time. At armature 239 and its front contact counting relay 222 prepares a locking circuit for itself in series with counting relay 223.

Interrupter relay 110, upon deenergizing a seventh time, again closes a circuit for the units of minutes buzzer B3 at armature 119 and its resting contact, starting the transmission of the seventh signal to the subscriber. At armature 118 and its front contact, interrupter relay 110 opens the original energizing circuit for counting relay 222, and at the same time removes the short circuit from the winding of counting relay 223. Counting relays 222 and 223 then lock up in series to grounded conductor 128. At armature 225 and its front contact counting relay 223 transfers the impulsing circuit over armature 118 and its front contact from ground to battery, and at armature 226 and its front contact it prepares a circuit for successively deenergizing the counting relays in the same order that they were energized.

The eighth time interrupter relay 110 energizes, armature 119 and its resting contact opens the circuit for the units of minutes buzzer B3,

terminating the seventh signal to the subscriber over conductors 28 and 29. At armature 118 and its front contact interrupter relay 110 closes a circuit from battery, armature 225 and its front contact, conductor 130, armature 118 and its front contact, armature 133 and its resting contact, conductor 129, armature 226 and its front contact, armatures 259 to 263, inclusive, and their respective front contacts, winding of counting relay 213, to grounded conductor 128. Counting relay 213 remains energized over this circuit but counting relay 212 is short circuited and restores to normal. Upon deenergizing, counting relay 212 closes a testing circuit from stop relay 112, conductor 128, armature 253 and its front contact, armature 247 and its resting contact, to the seventh bank contact of the registers. The absence of ground on the seventh bank contact prevents stop relay 112 from operating at this time.

The eighth time interrupter relay 110 deenergizes, a circuit is closed again at armature 119 and its resting contact for the units of minutes buzzer B3, starting the transmission of the eighth signal to the subscriber. At armature 118 and its front contact interrupter relay 110 opens the circuit for counting relay 213. Counting relay 213 deenergizes and at armature 253 and its front contact opens the testing circuit for the seventh bank contact of the registers. At armature 263 and its resting contact counting relay 213 prepares a circuit for short circuiting counting relay 214 and for holding counting relay 215 energized.

The ninth time interrupter relay 110 energizes, armature 119 and its resting contact opens the circuit to the units of minutes buzzer B3, terminating the eighth signal to the subscriber over conductors 28 and 29. At armature 118 and its front contact interrupter relay 110 closes a circuit from battery, armature 225 and its front contact, conductor 130, armature 118 and its front contact, armature 133 and its resting contact, conductor 129, armature 226 and its front contact, armatures 259 to 262, inclusive, and their respective front contacts, armature 263 and its resting contact, winding of counting relay 215, to grounded conductor 128. Counting relay 215 remains energized over this circuit but counting relay 214 is short circuited and restores to normal. Upon deenergizing, counting relay 214 closes a testing circuit at armature 248 and its resting contact, from the slow-acting stop relay 112 to the eighth bank contact of the registers. This time a circuit is completed from ground, armature 139 and its front contact, conductor 122, wiper 208 and eighth bank contact of the units of minutes register UR, armature 248 and its resting contact, armature 254 and its front contact, conductor 121, winding of stop relay 112, to battery. Stop relay 112 energizes over this circuit and at armature 138 and its front contact closes an obvious locking circuit for itself. At armature 136 and its resting contact stop relay 112 removes the locking ground from conductor 128, restoring relays 210, 211, and 215 to 223, inclusive, to normal, and at armature 133 and its resting contact opens the impulsive circuit over armature 118 and its front contact. Pick-up relay 210, upon deenergizing, opens the circuit to buzzer B3 at armature 240 and its front contact. Relay 211, upon deenergizing, restores the pick-up circuit at armature 244 and its resting contact but without effect at this time, because the pick-up circuit is opened at armatures 115 and 116. Counting

relay 215, upon restoring to normal, opens the original energizing circuit for stop relay 112, at armature 254 and its front contact. The removal of the locking ground from conductor 128, at armature 136 and its resting contact, opens the circuit of the normally energized relay 113 and it deenergizes. At armature 141 and its front contact relay 113 removes the short circuit from the lower winding of the two-step sequence relay 107. Sequence relay 107 then locks itself in its second step from ground, resting contacts controlled by armature 144, contact A of relay 107, both windings of relay 107 in series to battery. Relay 113 also opens the locking circuit for stop relay 112 at armature 137 and its front contact. Stop relay 112 does not deenergize, however, because it is now locked to ground at armature 145 and its front contact. Stop relay 112 remains locked to ground at armature 145 and its front contact until the time signaling device is in position to start transmitting another complete time signal.

Sequence relay 107, upon energizing in its second step, pulls armature 146 in contact with weighted spring 108. Weighted spring 108 vibrates and when it comes to rest closes an obvious circuit to slow-acting relay 104. The weighted spring 108 is provided to give an additional delay between the transmission of each complete time signal by the signaling device.

At armature 144 and its front contact relay 104 closes the first cut-off circuit for the differentially wound relay 8 of the time trunk circuit TTC from ground, armature 144 and its front contact, armature 147 and its front contact, conductor 33, armature 44 and its front contact, armature 14 and its resting contact, lower winding of differential relay 8, to battery. Upon energizing, differentially wound relay 8 prepares a circuit for its upper winding at armature 47, and at armature 19 and its front contact it closes another point in the locking circuit for pick-up relay 11. At the resting contacts controlled by armature 144 relay 104 opens the locking circuit for sequence relays 105 to 107, inclusive.

Sequence relays 105 to 107, inclusive, deenergize. At armatures 145 and 146 sequence relay 107 opens the circuits for relays 112 and 104, respectively. Stop relay 112 subsequently deenergizes and places ground on conductor 128, operating relay 113. Upon energizing, relay 113 closes a circuit for energizing sequence relay 105 in its first step from ground, armature 141 and its front contact, armatures 142 and 143 and their respective resting contacts, upper winding of sequence relay 105, to battery. Relay 104, upon deenergizing, prepares a locking circuit for sequence relay 105 at the resting contacts controlled by armature 144, and it opens the initial energizing circuit for differential relay 8 of the time trunk circuit TTC at armature 144 and its front contact.

When the initial energizing circuit to the lower winding of differential relay 8 is opened, it locks up in series with relay 9 from battery, lower winding of relay 8, armature 20 and its front contact, lower winding of relay 9, armature 41 and its front contact, to ground. Relay 9 also energizes over this circuit and closes an obvious locking circuit for itself over its upper winding and armature 48 and its front contact. At armature 18 and its resting contact relay 9 opens a point in the locking circuit for pick-up relay 11, and at armature 14 and its resting contact it opens a point in the initial energizing

circuit for differential relay 8. At armatures 16 and 17 and their respective front contacts, relay 8 prepares a busy tone circuit for the subscriber, and at armature 15 and its front contact it prepares a circuit for the upper winding of differential relay 8.

The subscriber has now heard one tone signal from the hours buzzer B1, three tone signals from the tens of minutes buzzer B2, and eight tone signals from the units of minutes buzzer B3, indicating that the time is 1:38 o'clock. The time signaling device is now in position to transmit the same signal to the subscriber again and the time trunk circuit TTC is in position to disconnect the subscriber from the tone signaling conductors and connecting him to the busy tone conductors after he has received the same time signal again.

It should be noted that the pick-up circuit over conductor 32 is closed at this time and will connect any subscriber that has seized a time trunk circuit to the time signaling conductors 28-29. The time trunk circuits cannot be connected to the time signaling device after the transmission of a time signal has started because the pick-up circuit over conductor 32 will be opened.

The operation of the time signaling device in transmitting the second time signal to the subscriber connected to time trunk circuit TTC is the same as has been hereinbefore described. However, after the last signal has been transmitted, relay 104 is operated again after the vibrating contact 108 comes to rest, and it opens the locking circuit for transfer relays 105 to 107, inclusive, at the resting contacts controlled by armature 144. At armature 148 and its front contact relay 104 closes the second cut-off circuit from ground, armature 148 and its front contact, conductor 34, armatures 15 and 47 and their respective front contacts, upper winding of differential relay 8, to battery. Differential relay 8 deenergizes and at armature 20 and its front contact opens the initial energizing circuit for the lower winding of relay 8, but relay 8 does not deenergize as it is locked up over its upper winding to ground at armature 41. At armature 19 and its front contact differential relay 8 opens the locking circuit for pick-up relay 11. Upon deenergizing, pick-up relay 11 disconnects the subscriber from the signaling conductors 28 and 29 at armatures 43 and 46 and their respective front contacts, and at armatures 43 and 46 and their respective resting contacts it connects the subscriber to the busy signaling conductors 26 and 27. The circuit for the busy signal to the subscriber is as follows: secondary winding of transformer 21 whose primary winding is connected to the usual busying machine, conductors 26 and 27, armatures 16 and 17 and their respective front contacts, armatures 38 and 42 and their respective front contacts, armatures 43 and 46 and their respective resting contacts, condensers 12 and 13, conductors 5 and 6, to the subscriber's line.

Ordinarily the subscriber will hang up his receiver after he has heard the complete time signal the first time. If he is uncertain as to what time was transmitted he may listen to the next complete time signal. However, it is undesirable to permit the subscribers to listen to the time signals indefinitely. Therefore, the equipment is arranged to connect him to the busy signaling conductors after he has heard the second complete time signal. In this way the

trunks to the signaling device are not tied up any longer than necessary. By hanging up his receiver the subscriber opens the loop circuit over which line relay 10 is energized. Upon de-energizing, line relay 10 removes the holding ground from relay 9 and the preceding switches at armature 41 and its front contact, and at armatures 38 and 42 and their respective front contacts it disconnects the busy signaling conductors 26 and 27 from the subscriber's line. The preceding switches restore to normal in the usual manner.

When relay 9 deenergizes the time trunk circuit TTC is in position to be seized again by any subscriber.

The resistances 24, 25, and 40, connected to the secondary windings of transformers 21, 22, and 23, respectively, reduce the volume of the tone signals transmitted over conductors 26 to 31, inclusive, so they are not unpleasantly loud when one subscriber is listening and at the same time they place an artificial load on these conductors. Therefore, there will be very little change in the volume of tone regardless of the number of subscribers simultaneously connected to the time signaling device.

The condensers 12 and 13 shown in the time trunk circuit TTC and the condensers 312 and 313 shown in Fig. 3 are of low capacity, to prevent subscribers connected to the multiplied conductors 28 and 29 from talking to each other. The condensers also limit the amount of current flow over any one subscriber's line, thereby maintaining the volume of the tone signals over long lines practically the same as over short lines.

An alternative arrangement for generating the tone signals to be transmitted over conductors 28 and 29 is to employ gongs or chimes, similar to those used in time clocks, in combination with magnets for striking the time. When this method of tone generating is used, it may be necessary to use a vacuum tube amplifier in conjunction with a transmitter placed in proximity to the gongs or chimes, by means of which the tones are picked up and amplified before being transmitted to the subscriber over conductors 28 and 29.

Automatic subscriber seizing time trunk circuit after the time signaling device has started transmitting a time signal

It is assumed that the time signaling device has started transmitting a time signal over conductors 28 and 29 and that a subscriber seizes the time trunk circuit TTC after the first two digits of a signal have been transmitted over the hours and tens of minutes buzzers B1 and B2, respectively.

Line relay 10, of the time trunk circuit TTC, energizes over the subscriber's loop circuit as before. This time, however, pick-up relay 11 does not operate because the pick-up circuit over conductor 32 is opened at one or more of the following armatures: armature 224 which opens the pick-up circuit while each digit is being transmitted, armature 116 which opens the pick-up circuit between the transmission of each digit, and armature 115 which holds the pick-up circuit open from the time the first digit is completed until the signaling device restores to normal after the complete time signal is transmitted.

With line relay 10 energized and with pick-up relay 11 deenergized, because a circuit is not completed over the pick-up conductor 32, a tick tone signal similar to the ticking of a clock is connected to the line to indicate to the subscriber

that a connection has been established to the time signaling device.

Interrupter relays 110 and 111 are intermittent-
ly operating, as has been hereinbefore described,
5 and each time relay 111 operates a circuit is closed
at armature 149 and its front contact from bat-
tery, resistance 114, armature 149 and its front
contact, primary winding of transformer 22, to
10 ground. The intermittent interruption of the
current in the primary winding induces a tick
tone in the secondary winding of the transformer
22, which is transmitted to the subscriber over
conductors 30 and 31, armatures 16 and 17 and
15 their respective resting contacts, armatures 38
and 42 and their respective front contacts, ar-
matures 43 and 46 and their respective resting
contacts, condensers 12 and 13, conductors 5 and
20 7, and the subscriber's loop. After the time signal
being transmitted by the signalling device is com-
pleted, a pick-up circuit is closed over conductor
25 32, and pick-up relay 11 energizes as before, dis-
connecting the subscriber's line from the tick tone
conductors 30 and 31 and connecting the line to
the time signaling conductors 28 and 29.

25 *Transmission of special signal when wipers of tens
or units of minutes registers are associated with
tenth bank contacts of the registers*

It will be assumed that the wipers of the tens
30 of minutes register TR and the units of minutes
register UR are associated with the tenth bank
contacts, and that the signaling device has trans-
mitted the time registered on the hours register
HR, as has been hereinbefore described. Se-
35 quence relay 106, upon energizing in its second
step after the hour signal has been transmitted,
closes a circuit from ground, armature 139 and its
resting contact, armature 140 and its front
contact, conductor 123, wiper 205 and tenth bank
40 contact of the tens of minutes register TR, con-
ductor 125, winding of relay 109, to battery. Re-
lay 109 energizes and at armature 150 and its
front contact places ground on conductor 126,
grounding the fourth bank contact of the reg-
45 ister. At armature 151 and its front contact re-
lay 109 prepares a circuit for buzzer B3, shunt-
ing out the intermittently operated armature 119
of interrupter relay 110. When pick-up relay 210
is energized by the operation of interrupter relay
50 110 it immediately closes a circuit to buzzer B2,
at armature 240 and its front contact starting
the transmission of the tens of minutes signal
over signaling conductors 28 and 29. This cir-
cuit remains closed until the counting relays have
55 tested the first four bank contacts of the register.
Interrupter relay 110 operates the counting re-
lays as has been described, testing each bank
contact of the registers in turn. The fifth time
interrupter relay 110 energizes a circuit is closed
60 at armature 118 and its front contact, energizing
counting relay 218. Upon energizing, counting
relay 218 closes a circuit to stop relay 112 from
ground, armature 150 and its front contact, ar-
mature 244 and its front contact, armature 256
65 and its resting contact, conductor 121, winding
of stop relay 112, to battery. Stop relay 112 ener-
gizes, removing the holding ground from con-
ductor 128 at armature 136 and its resting con-
tact, deenergizing relays 210 to 217, inclusive, and
70 at armature 133 and its resting contact it opens
the circuit of counting relay 218. Relays 210 to
218, inclusive, deenergize. The falling back of
pick-up relay 210 opens the circuit to buzzer B2
at armature 240 and its front contact, termi-
75 nating the tone signal being transmitted over

conductors 28 and 29. Relay 113 deenergizes as
before, removing the short circuit from the lower
winding to the sequence relay 106. Sequence re-
lay 106 locks up in its second step, transferring
the marking ground at armature 139 from con-
5 ductor 123 and wiper 205 of the tens of minutes
register TR, to conductor 122 and wiper 208 of
the units of minutes register UR. The removal
of ground from wiper 205 opens the energizing
circuit of relay 109 and it deenergizes.

10 The operation of the equipment, with wipers
207 and 208 of the units of minutes register UR
associated with the tenth bank contacts, is the
same as described above. However, the tone sig-
nal is in this case transmitted by the units of 15
minutes buzzer B3.

Relay 109 and armature 151 and its front con-
tact are provided to shunt out the intermittently
20 operated armature 119 of the interrupter relay
110 and armature 150 and its front contact is
provided to ground the fourth bank contact of
the tens and units of minutes registers TR and
UR, respectively. With this arrangement, in-
25 stead of transmitting ten short signals or just
providing a silent period to indicate zero, a long
continuous signal is transmitted equivalent to the
transmission of approximately four short signals.

The time transmitted with the registers in the
position described above is 1:00 o'clock.

30 *Setting of the registers by the master clock*

The setting of the hours register HR, the tens
of minutes register TR, and the units of minutes
register UR, by momentary impulses from the
master clock, will now be described.

35 The master clock, shown to the right of trans-
former 23, is connected to the time signaling de-
vice over conductor 37 and is arranged to momen-
tarily close its contacts 35 at the end of every
40 minute. Every time the clock operates its con-
tacts 35, a momentary circuit is closed from
ground, contacts 35 of the clock, conductor 37,
upper winding of relay 101, to battery. It will
be assumed that relay 107 is energized, preventing
45 relay 101 from being locked to ground at ar-
mature 152 and its resting contact. Relay 101 ener-
gizes and closes an obvious circuit for relay 102,
the functions of which will be described later.
It also closes a circuit from ground, armature 154
50 and its front contact, conductor 121, winding of
magnet 209 of the units of minutes register UR,
to battery. Magnet 209 energizes, but is arranged
to advance its wipers 207 and 208 when it is de-
energized. Relay 101 being momentarily ener-
55 gized, subsequently deenergizes and opens the cir-
cuit for magnet 209. Magnet 209 deenergizes, ad-
vancing its wipers 207 and 208 to the next bank
contact. Each minute magnet 209 is again momen-
tarily energized over the above circuit, ad-
60 vancing its wipers 207 and 208 to the next bank
contact.

65 Every time wipers 207 and 208 are associated
with the ninth bank contacts, the next time relay
101 is momentarily energized a momentary circuit
is completed to magnet 206 of the tens of minutes
register TR, as well as magnet 209 of the units of
minutes register UR, from ground, armature 154
and its front contact, conductor 121, wiper 207
and the ninth bank contact of the units of min-
utes register UR, winding of magnet 206, to bat-
70 tery. This time wipers 204 and 205 of the tens
of minutes register TR and wipers 207 and 208
of the units of minutes register UR are advanced
to the next bank contacts.

75 When wipers 204 and 205 are associated with

the fifth bank contact of the tens of minutes register TR and wipers 207 and 208 are associated with the ninth bank contacts of the units of minutes register UR, the next time relay 101 is momentarily energized by the master clock a momentary circuit is completed to magnet 203 of the hours register HR as well as to magnets 206 and 209 of the tens and units of minutes registers TR and UR, respectively, over conductor 121, wiper 207, and ninth bank contact of the units of minutes register UR, wiper 204 and fifth bank contact of the tens of minutes register TR, winding of magnet 203, to battery. This time all the wipers of the registers are advanced to the next bank contact. Therefore, each minute the wipers of the units of minutes register UR are advanced one step, every ten minutes the wipers of the tens of minutes register TR are advanced one step, and each hour the wipers of the hours register HR are advanced one step. In this manner the exact time of day is always registered by the time signaling device.

The bank contacts of the registers that are not being used are grounded through the interrupter contacts of the respective magnets. Each time a wiper is advanced to one of the grounded contacts of the bank it closes a circuit to its respective magnet. The magnet, upon energizing, opens the energizing circuit at its interrupter contact, advancing the wipers to the next bank contact.

Change in time while the subscriber is receiving the first complete time signal

It will be assumed that the subscriber is connected to the time signaling device and that he is receiving the time signal transmitted over conductors 28 and 29, the first time.

The clock momentarily operates its contact 35, energizing relay 101 as before. However, with the time signal partially transmitted, sequence relay 107 will be deenergized and at armature 152 and its resting contact an obvious locking circuit is closed for the lower winding of relay 101. At armature 154 and its front contact relay 101 closes an obvious circuit for relay 102 and at the same time it closes a circuit over conductor 121, energizing magnet 209 of the units of minutes register UR. Upon energizing, relay 102 opens the locking circuit of impulse absorbing relay 103 at armature 155 and its resting contact, and at armature 156 and its front contact it closes an additional locking circuit for sequence relays 105 to 107, inclusive. Upon deenergizing, the impulse absorbing relay 103 disconnects the circuit for differential relay 8 at armature 147 and its front contact, and at the resting contact it prepares a circuit for its lower winding.

The impulse absorbing relay 103 is deenergized at this time to prevent a subscriber that is receiving a time signal the first time from being disconnected after he has received the second time signal. For example, a subscriber is connected to the time signaling device and is receiving the time, which is 1:38 o'clock. Now then, if the time is changed by the operation of relay 101 by the clock, the impulse absorbing relay 103 is deenergized and when the transmission of time signal 1:38 is completed and relay 104 is energized, the circuit usually closed over conductor 33 to operate the differential relay 108 is now closed to again energize the impulse absorbing relay 103. By this arrangement the signal 1:38 o'clock is not counted, permitting the subscriber to receive two complete signals of the new time, 1:39 o'clock.

It will be assumed that the time signaling device has now transmitted a complete time signal and that sequence relays 105 to 107, inclusive, have been locked up to ground at armature 156 and its resting contact and to ground at the resting contacts controlled by armature 144. Upon energizing, sequence relay 107 opens the holding circuit for relay 101 at armature 152 and its resting contact. Upon deenergizing, relay 101 opens the circuit of relay 102 and magnet 209. Magnet 209 deenergizes and advances its wipers 207 and 208 to the next bank contact. Relay 102 being slow to release remains operated a short time after its energizing circuit is opened. Relay 101, upon deenergizing, closes a circuit from ground, armature 157 and its resting contact, armature 158 and its front contact, interrupter contacts and winding of buzzer B4, to battery.

Buzzer B4 vibrates and transmits a tone signal over conductors 28 and 29 in the same manner as described in connection with buzzers B1 to B3, inclusive, indicating to the subscriber that the time has changed and that the next signal to be transmitted will be the new time. Upon deenergizing, relay 102, at armature 158 and its front contact, opens the circuit for buzzer B4 terminating the "change in time" signal, at armature 156 and its front contact it opens a point in the locking circuit for the sequence relays 105-107, inclusive, and at armature 155 and its resting contact it prepares a locking circuit for impulse absorbing relay 103. Relay 104 is energized when the vibrating contact 108 comes to rest, and at armature 144 and its front contact it closes a circuit for the lower winding of impulse absorbing relay 103. Impulse absorbing relay 103 operates in its first step closing contacts A only. Relay 104 subsequently deenergizes as has been hereinbefore described. Upon deenergizing, relay 104 opens the circuit for the lower winding of impulse absorbing relay 103 and at the same time removes the short circuit from the upper winding. Impulse absorbing relay 103 immediately locks up in its second step from ground, armature 155 and its resting contacts, contact A and both windings of impulse absorbing relay 103 in series, to battery. The equipment is now in position to transmit the new time signal.

The time signaling device can be arranged to transmit the special tone from buzzer B4, to indicate a change in time, exactly at the beginning of each minute. This can be done by arranging contacts 35 of the master clock to close about eight or ten seconds before the new minute is to begin and to open them exactly on the minute. By closing the circuit to relay 101, over contacts 35 of the master clock, about eight or ten seconds before the new minute is to begin, the signals being transmitted over conductors 28 and 29 will have time to be completed but another signal cannot be started after it is completed until relay 101 is released by the opening of contacts 35 of the master clock. The release of relay 101 closes a circuit to buzzer B4 and the special tone signal is heard by the subscriber, indicating that the time is changed. The wipers of the registers will be advanced to the next bank contact and the signaling device will start the transmission of the new signal.

Simplified time trunk circuit

When the time trunk circuit shown in Fig. 3 is used, only the signaling conductors 28 and 29

from the time signaling device are required to transmit the signal to the subscriber.

When a subscriber dials and a selector associates its wipers with bank contacts 302 to 303, 5 inclusive, line relay 301 immediately energizes over the subscriber's loop circuit in the same manner as line relay 10 of time trunk circuit TTC. Upon energizing, line relay 301 connects the subscriber to the time signaling conductors, 10 associated front contacts, and at armature 341 and its front contact it grounds the release trunk of the preceding switches, holding them operated in the well-known manner.

The subscriber is immediately connected to 15 the time signaling conductors and is not disconnected until he hangs up his receiver.

What is claimed is:

1. In combination, an impulse sender, a plurality of counting relays, a plurality of registers 20 for registering the time of day, and means controlled by said impulse sender, said counting relays and said registers for continuously transmitting the time registered on said registers.

2. In combination, a plurality of transfer relays, a plurality of time registers, means controlled by said transfer relays for making the registers effective in proper sequence, an impulse sender, a plurality of counting relays, and means controlled by said impulse sender and said counting 30 relays for operating said transfer relays in proper sequence.

3. In combination, a relay operated by momentary impulses from a clock, a plurality of registers, means controlled by the operation of 35 said relay for operating said registers to register the time of day, means for transmitting signals indicative of the registration, means for preventing said relay from operating said registers while said signals are being transmitted, and means for 40 preventing any signals from being transmitted while said relay is operating said registers.

4. In combination, a signaling device, a plurality of time registers, a plurality of counting relays for counting the number of signals to be 45 transmitted by said device, means including said registers for stopping the counting operations at variable points, and means for providing a predetermined long pause between the transmission of complete time signals and a short pause between the transmission of component parts of 50 each complete signal.

5. In a time signaling system, a plurality of time registers, a plurality of signaling devices for generating tone signals differing in pitch, and 55 means for operating said devices in accordance with the setting of said registers, respectively.

6. In a time signaling device, means for transmitting tone signals of a predetermined frequency indicative of the hour, means for transmitting tone signals of a higher predetermined frequency indicative of the group of minutes, and means for transmitting tone signals of a still higher predetermined frequency indicative of the minute within the group.

65 7. In a time signaling system, means for transmitting the time of day, a trunk multiple common to a plurality of subscribers, means for connecting said subscribers to said common trunk multiple for receiving the time of day transmitted by said first mentioned means, and means controlled from said first means for disconnecting each subscriber from said common trunk multiple after receiving a predetermined number of time signals.

75 8. In combination, a source of information ar-

ranged to automatically transmit information at intervals, a plurality of subscribers' lines, a plurality of subscribers' connecting links, a trunk multiple common to said connecting links, and means responsive to the seizure of a connecting link by any of said subscribers for connecting the seized link to said trunk multiple for receiving said information.

9. In combination, a source of information arranged to automatically transmit information at intervals, a plurality of subscribers' lines, a plurality of subscribers' connecting links, a trunk multiple common to said connecting links, means responsive to the seizure of a connecting link by any of said subscribers for connecting the seized link to said trunk multiple for receiving said information, and means for disconnecting each subscriber from said trunk multiple after said information has been received a predetermined number of times.

20 10. In a time signaling system, a time signaling device, a trunk circuit for connecting subscribers to said time signaling device, and means responsive to the transmission of the same complete time signal a second time for disconnecting the subscriber from said time signaling device.

11. In a time signaling system, a time signaling device, a trunk circuit for connecting subscribers to said time signaling device, means responsive to the transmission of a time signal to a subscriber a second time for disconnecting the subscriber from said time signaling device, and means responsive to a change in the time signal before the same has been twice transmitted to such subscriber for preventing said subscriber from being disconnected until the complete new time signal has been transmitted twice.

25 12. In combination, a plurality of trunk circuits accessible to telephone subscribers, a plurality of conductors common to said trunk circuits, a time signaling device individual to said plurality of conductors, and means responsive to the seizure of a trunk circuit by a subscriber for connecting said trunk circuit to certain of said conductors.

40 13. In combination, a plurality of trunk circuits accessible to telephone subscribers, a plurality of conductors common to said trunk circuits, a time signaling device individual to said plurality of conductors, means responsive to the seizure of a trunk circuit by a subscriber for connecting said trunk circuit to certain of said conductors, and means for connecting said trunk circuit to certain other conductors when said signaling device is in a predetermined position.

45 55 14. In a time signaling system, a plurality of registers for registering the time of day, means for setting said registers, a signaling device arranged to repeatedly transmit intermittent tone signals corresponding in number to the setting of each of said registers, and means for providing a uniform short pause after the transmission of the signals corresponding to the registration on each of said registers except the last and a predetermined long pause after the transmission of signals corresponding to the registration on the last of said registers.

60 65 70 75 15. In combination, a time signaling device accessible to subscribers over a plurality of trunk circuits, means in said device for transmitting tone signals of predetermined frequencies and at predetermined intervals indicative of the time of day, and means independent of subscriber control for automatically disconnecting each sub-

- scriber after a predetermined number of complete time signals have been heard.
16. In a time signaling system, a plurality of registers for registering the time of day, a plurality of counting relays, means including said counting relays for successively making tests of each of said registers, and means responsive to the setting of each of said registers for stopping the operation of said counting relays at different predetermined intervals in accordance with the time registered at any given instant. 5
17. In a time signaling device, a plurality of registers, a plurality of counting relays, a plurality of conductors extending from each of said registers to said counting relays, means for successively marking conductors from said registers to indicate the time registered thereon, means for operating said counting relays a plurality of times until each marked conductor has been encountered, and means for restoring the operated counting relays after each of said marked conductors is encountered. 10
18. In a time signaling device, a register, a plurality of counting relays, a plurality of conductors extending from said register to said counting relays, means for marking one of the conductors from said register to indicate the time registered thereon, means for operating each of said counting relays in turn until the marked conductor is encountered, and means responsive when all of said counting relays have been operated without encountering said marked conductor for releasing each of said counting relays in turn until the marked conductor is encountered. 15
19. In combination, a plurality of trunk circuits accessible to telephone subscribers, a plurality of conductors common to said trunk circuits, a time signaling device individual to said plurality of conductors, means responsive to the seizure of a trunk circuit for transmitting a tick-tock tone signal over certain of said common conductors to the connected subscriber to indicate that the time signaling device has been seized, and means for disconnecting said tick-tock signals and connecting said trunk circuit to certain other of said conductors when said time signaling device is in a position to transmit the time of day. 20
20. In a time signaling system, means for transmitting a tick-tock signal indicative of the time of day and for subsequently transmitting the time of day, a trunk multiple common to a plurality of subscribers, means for connecting said subscribers to said common trunk multiple for receiving said tick-tock signals, and means for subsequently disconnecting said tick-tock signal so the subscribers can receive the time of day. 25
21. In a time signaling system, a trunk circuit accessible to telephone subscribers, means for extending a connection from a calling subscriber's line to said trunk circuit, a time signaling device, means in said device for transmitting a tick-tock tone signal, signals indicative of the time of day, and a disconnect signal, and means including said trunk circuit for connecting said tick-tock signal to said subscriber's line, for disconnecting said tick-tock tone signal and connecting said time signal, and for disconnecting said time signals and connecting said disconnect signal. 30
22. In a time signaling system, a plurality of devices for generating tone signals differing in frequency, a like plurality of clock-controlled registers for registering the time of day, means for operating the respective devices in accordance with the setting of the respective registers 35
- to transmit tone signals indicative of the time registered, a special device for generating a tone signal of a higher frequency than the above-mentioned devices, and means responsive to a change in the time registered on said registers for operating said special device to transmit a tone signal indicative of a change in the time. 5
23. In a telephone system, a time signaling device comprising clock-controlled registers for registering the time of day, a plurality of tone generators, a counting mechanism, an impulse sender for simultaneously transmitting impulses to said counting mechanism and said tone generators, a transfer device for rendering each of the registers effective in turn and for simultaneously rendering the associated tone generator effective to the impulses transmitted thereto, a trunk circuit accessible to telephone subscribers, and means in said trunk circuit for connecting telephone subscribers to signaling conductors over which tone signals indicative of the time of day are transmitted by said tone generators. 10
24. In a telephone system, a time signaling device comprising a plurality of registers for registering the time of day, a like plurality of tone generators for transmitting tone signals indicative of the time registered, a transfer device for rendering the registers and tone generators effective in pairs, a counting mechanism, an impulse sender for transmitting impulses to the effective tone generator and for simultaneously controlling said counting mechanism to count the number of impulses transmitted to the effective tone generator, and means for preventing further impulses from being transmitted to the effective tone generator when the number of impulses transmitted correspond to the setting of the effective register. 15
25. In a time signaling system, a register having a plurality of positions corresponding, respectively, to successive intervals of time, means responsive to the lapse of each interval for advancing said register to its next position, time-signaling means, time-controlled means for periodically operating said signaling means and for simultaneously searching for the instant position of said register, and means for stopping the operation of the signaling means each time the instant position is located. 20
26. In a telephone system, a signaling circuit, a plurality of signal-current generators, each for generating current of a particular frequency, means for connecting said generators to said circuit to produce time signals therein in code, time-controlled means for changing the code of successive elapsed time intervals, whereby any code signal will be indicative of the time at that instant, and means for connecting subscribers' lines to said circuit to enable the subscribers to hear said code signals. 25
27. In a telephone system, a signal-current generator for generating current of a frequency indicative of a particular unit of time, another generator for generating current of a frequency indicative of a different unit of time, a signaling circuit, means for associating said generators with said circuit to produce coded time signaling currents therein, time-controlled means for altering the code with the lapse of each time unit, and means for connecting subscribers' lines to said circuit to enable the subscribers to receive the time by means of said code-signaling currents. 30
28. In a time signaling system, a register reset at predetermined intervals to register the time of day, means for transmitting tone signals in- 75

dicative of the time of day registered a plurality of times after each resetting operation, and means for transmitting a special tone signal each time the register is reset to indicate that the next time signal will be the exact time.

29. In a telephone system, a register for registering the time of day, time-controlled means for changing the registration at intervals, a signaling circuit, time-signaling means for transmitting the time of day over said circuit a number of times for each registration, a tone generator automatically operated each time the registration is changed to transmit a tone signal over said circuit to indicate that the first time signal transmitted thereafter will be the exact time, and means for connecting subscribers' lines to said circuit to receive said signals.

30. In a time signaling system, means operated periodically for transmitting tone signals, means operated at longer periods for changing the time signals in accordance with the change in time, and means for transmitting a special signal accompanying each time signal the first time such signal is transmitted.

31. In a system for transmitting information from a central station to outlying stations, a storage device at the central station in which a variable digit indicative of a variable characteristic of an item of information is stored, said device including contact means resettable to change the value of the stored digit, a continuously operating impulse sender associated with said storage device, a signal transmitter controlled by said sender, said transmitter including means for sending to any associated outlying station a series of impulses of like character which are representative of the stored digit, and means responsive to a signal sent from an outlying station desiring information for associating such station with said transmitter.

32. In a system for transmitting information from a central station to subscribers' stations, a plurality of storage devices at the central station on which digits representing certain information are stored, a sender operating periodically to send impulses in accordance with the digits stored in said storage devices, transmitting means responsive to such impulses to generate a series of signals representative of said digits, a plurality

of link circuits accessible to subscribers responsive to calls for information, means in each link circuit for connecting the same to said transmitting means to receive the digit signals generated thereby, and means for preventing a link circuit taken for use while a series of signals is being generated from being connected to said transmitting means until the series is finished.

33. A system for transmitting information from a central station to outlying stations, said system comprising information storing means at the central station which is resettable to change the information stored therein from time to time, a link circuit at the central station accessible to the outlying stations through automatic selecting mechanism, transmitting means at the central station for sending out information by means of electrical signals over said link circuit to any outlying station connected thereto, controlling apparatus, circuit connections over which said controlling apparatus operates said transmitting means periodically in accordance with the setting of said storing means, and means for preventing the stored information from being changed while said controlling apparatus is operating said transmitting means.

34. In a signaling system, registering apparatus, means for periodically changing the setting of said apparatus to maintain it set in accordance with the time of day, means controlled in accordance with the setting of said registering apparatus at a given time for transmitting a group of time signals, and means effective upon each change in the setting of said registering apparatus for transmitting a distinctive signal indicative of the fact that the next group of time signals transmitted will be different from the preceding group.

35. In a time signaling system, a register having a plurality of positions, time controlled means for periodically advancing said register from one position to the next, means for testing said positions successively to determine the position of the register, means for starting the testing operation and for continuing it until the instant position of the register is determined, and means effective while successive positions are being tested for transmitting time signals.
